2 Sheets-Sheet 2

UNITED STATES PATENT OFFICE.

HENRY W. GRIFFIN, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed May 7, 1925. Serial No. 28,574.

My invention relates to railway signaling apparatus, and particularly to apparatus of the controlled manual type for stretches of single track over which traffic must at times move in opposite directions.

I will describe two forms of signaling apparatus embodying my invention, and will then point out the novel features thereof in claims.

10 In the accompanying drawings, Fig. 1 is a diagrammatic view showing one form of signaling apparatus embodying my invention. Fig. 2 is a view showing the circuit controlling positions of levers L^A and L^B in Fig. 1. Fig. 3 is a diagrammatic view showing a modification of the signaling apparatus shown in Fig. 1 and also embodying my invention. Fig. 4 is a view showing the circuit controlling positions of the levers L^A 20 and L^B in Fig. 3.

Similar reference characters refer to similar parts in each of the several views.

Referring first to Fig. 1, the reference characters 1 and 1^a designate the track rails 25 of a stretch of railway track between two stations A and B. The stretch of track between these stations is divided by insulated joints 7 into a plurality of track sections each of which is provided with a track circuit comprising a track battery 8 and a track relay designated by the reference character T, with a distinguishing exponent.

Located at the station A is an interlocking machine comprising a traffic lever L^A and a signal lever D^A . Located at station B is another interlocking machine comprising a traffic lever L^B and a signal lever D^B . Each of the traffic levers L^A and L^B when swung to the left occupies what is known as the "normal" position, and when swung to the right it occupies what is known as the "reverse" position. As shown in the drawing, each of these levers is in the normal position, wherein in each contact N associated with the lever is closed. When each of these levers is in its reverse position, each contact R associated with the lever is closed. When the lever is in the middle position, each contact C associated with the lever is closed. These three positions of the lever are indicated diagrammatically in Fig. 2.

Located adjacent the station A is a signal S^A for governing the entrance of trains moving toward the left into the stretch of track between the stations A and B. Located ad-

jacent station B is a similar signal S^B for governing the entrance of trains moving toward the right into the stretch of track between the stations A and B. Signal S^A is controlled by lever D^A in such manner that when this lever is in the normal position the circuit for the signal is opened and so the signal indicates stop, whereas when the lever moves to its reverse position the circuit for the signal is closed and the signal then indicates proceed. The control of signal S^B by lever D^B is similar to the control of signal S^A by lever D^A .

The levers L^A and D^A are interlocked in such manner that when lever L^A is reverse lever D^A is locked in the normal position, that is, in such position that signal S^A indicates stop. Levers L^B and D^B are interlocked in such manner that when lever L^B is in the normal position lever D^B is locked in the normal position, so that signal S^B indicates stop. In order to release signal lever D^B lever L^B must be reversed.

Traffic lever L^A is provided with a magnet-operated lock G^A , comprising a segment 37 fixed to the lever L^A and cooperating with a latch 38 controlled by a magnet 2^A. When magnet 2^A is de-energized, the lock G^A prevents movement of lever L^A from its middle position to its normal position, but the lever is free to move from normal to reverse positions without energization of magnet 2^A. Lever L^B is provided with a similar lock G^B , controlled by a magnet 2^B, the arrangement being such that the lock prevents the lever from moving from its middle position to its reverse position unless magnet 2^B is energized. Lever L^B is free to move from its reverse to its normal position, however, without energization of magnet 2^B.

The lock G^A controls a lock contact 9^A, which is closed when the latch 38 is in its lower position and open when the latch is elevated. The lock G^B controls a lock contact 9^B in a similar manner.

As shown in the drawing, levers L^A and L^B are both in normal positions. The towerman at station A may therefore reverse lever D^A to clear signal S^A and to thereby allow trains moving in the direction indicated by the arrow to enter the stretch of track between the two stations. Lever D^B is locked in its normal position, however, so that signal S^B cannot be cleared.

With the parts in the positions shown in

the drawing, a circuit is closed which passes from battery H^B , through wire 39, lock contact 9 ^{B} , wire 10, normal contact N ^{2} of lever L ^{B} , wire 11, contact 12 of track relay T $'$, wire 13, contact 14 of track relay T ^{2} , wire 15, contact 16 of track relay T ^{3} , wire 17, winding of relay F ^{A} , wire 18, contact N ^{5} on lever L ^{A} , resistance 6 ^{A} , wire 19, push button P ^{A} , wire 20, contact 21 of track relay T ^{3} , wire 22, contact 23 of relay T ^{2} , wire 24, contact 25 of relay T $'$, wire 26, winding of relay F ^{B} , wire 27, push button P ^{B} , wire 28, normal contact N ^{3} on lever L ^{B} , and wire 29 to battery H^B . This circuit causes relays F ^{A} and F ^{B} to be energized, and these relays in turn cause indicators E ^{A} and E ^{B} to be lighted. The circuit for indicator E ^{A} passes from battery 5 ^{A} , through contact 40 of relay F ^{A} , and the indicator E ^{A} to battery 5 ^{A} . The circuit for indicator E ^{B} is controlled in a similar manner by contact 40 of relay F ^{B} , and is supplied with current by a battery 5 ^{B} . These indicators E ^{A} and E ^{B} being lighted, inform the towermen that the circuit between the two stations is intact and that the stretch of track between these towers is unoccupied.

I will now assume that the towerman at station B wishes to permit a train moving from left to right to enter the stretch of track between the two stations. To do this the operator at station B signals the operator at station A by operating push button P ^{B} in accordance with a prearranged code, such, for example, as three successive openings of the circuit, thereby causing relay F ^{A} to become de-energized three times, with the result that indicator E ^{A} becomes extinguished three times. If the operator at station A is ready to permit reversal of traffic, he responds by operation of his push button P ^{A} in accordance with a prearranged code, thereby causing indicator E ^{B} at station B to flash. The operator at station A then shifts his traffic lever L ^{A} to the reverse position. The reversal of lever L ^{A} functions to include battery H ^{A} in the circuit hereinbefore traced. The portion of this circuit at station A then passes from wire 17, through relay F ^{A} , wire 18, reverse contact R ^{4} , wire 32, battery H ^{A} , wire 31, lock contact 9 ^{A} , wire 30, reverse contact R ^{5} , wire 19, and push button P ^{A} to wire 20. During the reversal of lever L ^{A} , the line circuit is momentarily opened between the time normal contact N ^{5} opens and reverse contacts R ^{4} , R ^{5} close; this causes indicator E ^{B} to be momentarily extinguished, thereby informing the operator at station B that lever L ^{A} has been reversed. The operator at station B then moves his lever L ^{B} to the middle position wherein contacts C $'$ and C ^{2} are closed, and this functions to exclude battery H ^{B} from the circuit and to include the lock magnet 2 B in the circuit. The portion of this circuit at station B then passes from wire 11, through contact C $'$, wire 33, lock magnet 2 B , wire 34, contact C ^{2} , wire 28, push button P ^{B} , wire 27 and winding of relay F ^{B} to wire 26. Lock magnet 2 B being energized, latch 38 is elevated to release the segment 37, so that lever L ^{B} may then be moved to its reverse position. When this lever is in its reverse position, the portion of the circuit at station B passes from wire 11, through reverse contact R ^{2} , resistance 6 ^{B} , wire 28, push button P ^{B} , wire 27, and winding of relay F ^{B} to wire 26. Traffic lever L ^{B} being in its reverse position, signal lever D ^{B} may now be reversed to cause signal S ^{B} to indicate proceed; traffic lever L ^{A} being in its reverse position, signal lever D ^{A} is locked in its normal position, so that signal S ^{A} cannot be cleared.

Relays F ^{A} and F ^{B} are now energized from battery H ^{A} , the resistance 6 ^{B} at station B being substituted for the lock magnet 2 B which is in the circuit at the time that the release of lever L ^{B} occurs.

With both levers L ^{A} and L ^{B} reversed, I will assume that the operator at station A desires to permit a train moving from right to left to enter the stretch of track between the stations. To do this, he signals the operator at station B through the medium of push button P ^{A} , the operator at station B acknowledges this signal by in turn signaling the operator at station A through the medium of push button P ^{B} , and the operator at station B then shifts his traffic lever L ^{B} to the normal position. This movement of lever L ^{B} opens contact R ^{2} , and restores battery H ^{B} to the circuit because of the closing of contacts N ^{2} and N ^{3} . The operator at station A then moves his traffic lever L ^{A} to the middle position, thereby closing contacts C ^{3} and C ^{4} , which contacts function to include the lock magnet 2 A in the circuit. The portion of the circuit at station A then passes from wire 17, through relay F ^{A} , wire 18, contact C ^{3} , wire 35, lock magnet 2 A , wire 36, contact C ^{4} and push button P ^{A} to wire 20. Lock magnet 2 A is then energized from battery H ^{A} , whereupon the lock G A is actuated to release lever L ^{A} , and the operator at station A then completes the movement of lever L ^{A} to its normal position. The parts of the apparatus are then restored to the positions in which they are shown in the drawing, so that lever D ^{A} may be reversed to cause signal S ^{A} to indicate proceed.

It will be noted that the releasing circuit for lock magnet 2 at each station includes the lock contact 9 at the other station. This insures that neither lever can be released unless the other lever is locked.

Located at station A are two direction indicators 3 A and 4 A , and each of which is preferably in the form of a lamp provided with an arrow on the outside of the lamp case. The arrow for lamp 3 A points to the left,

and the arrow for lamp 4^A points to the right. Lamp 3^A is provided with a circuit including a normal contact N^4 on lever L^A , and lamp 4^A is provided with a circuit controlled by reverse contact 3^A on lever L^A . It follows that when lever L^A is in the normal position, lamp 3^A is lighted, and that when the lever L^A is in the reverse position, lamp 4^A is lighted. Station B is provided with similar indicators 3^B and 4^B , which are controlled by normal contact N' and reverse contact R' , respectively, on lever L^B .

With the apparatus shown in Fig. 1, the indicator relays F^A and F^B are in series with the lock magnet 2^A or 2^B at the time of unlocking lever L^A and L^B , respectively. Inasmuch as this may require a voltage higher than that generally used at interlocking plants, it may in some instances be desirable to exclude the relays F^A and F^B from the circuit at the time of unlocking, and when this is desirable it may be accomplished with the apparatus shown in Fig. 3.

Referring now to Fig. 3, the apparatus here shown is similar to that shown in Fig. 1, except that each traffic lever L has more contacts, and these contacts control the lock magnets and the indicator relays in a slightly different way. As shown in Fig. 4, each traffic lever has a normal position N, a reverse position R, a middle position C, a normal indication position X, a reverse indication position Y, a position W between positions N and X, and a position Z between positions Y and R.

When the parts of the apparatus are in the positions shown in the drawing, that is, when both traffic levers are in normal positions, the indication relays F and the push buttons P are connected in series in a circuit which is supplied with current from battery H^B at station B. This circuit passes from battery H^B , through wire 39, lock contact 9^B , wire 10, contact N^X on lever L^B , wire 11, upper contacts of the three track relays, wire 17, contact N^x , wire 51, relay F^A , wire 43, contact N^c , wires 44 and 47, push button P^A , wire 20, lower contacts of the three track relays, wire 26, push button P^B , wire 28, contact N^s , wire 41, relay F^B , wire 42, contact N^2 , and wire 29 to battery H^A .

Lever L^A being in the normal position, signal lever D^A may be moved to the reverse position to permit traffic moving from right to left to enter the stretch of track between the two stations.

When it is desired to reverse the direction of traffic, and the operators have accordingly signaled each other as before by push buttons P, the operator at station A moves his lever to position Y or position Z or some place between these two positions, and the operator at station B moves his traffic lever L^B to reverse indication position Y, in which

position this lever is stopped by the lock G^B . An unlocking circuit for lever L^B is then closed, which circuit passes from battery H^A at station A, through wire 31, lock contact 9^A , wire 46, lever contact Y^B , wire 47, push button P^A , wire 20, track relay contacts, wire 26, push button P^B , wire 50, contact Y' , wire 49, lock magnet 2^B , wire 48, contact Y^2 , wire 11, track relay contacts, wire 17, contact Y^2 , and wire 45 to battery H^A . It will be noted that this circuit does not include either relay F^A or F^B . The energization of lock magnet 2^B releases lever L^B , whereupon the operator moves this lever to the reverse position and the operator at station A completes the movement of lever L^A to the reverse position. Lock magnet 2^B is then excluded from the circuit and the relays F^A and F^B are included in the circuit, the circuit then passing from battery H^A , through contact 9^A , lever contact Y^B , push button P^A , wire 20, track relay contacts, wire 26, push button P^B , contact R^s , relay F^B , contact R^2 , wire 11, track relay contacts, wire 17, contact R^4 , relay F^A , contact R^5 to battery H^A .

To restore the apparatus to its normal condition the operator at station B returns his lever L^B to such position that contact W^x is closed, and the operator at station A returns his lever L^A to its reverse indication position. Lock magnet 2^A is then energized by a circuit which passes from battery H^B , through contact 9^B , contact N^x , wire 11, track relay contacts, wire 17, contact X^3 , lock magnet 2^A , contact X^4 , push button P^A , wire 20, track relay contacts, wire 26, push button P^B and contact W^x to battery H^B . Lever L^A being released by the energization of magnet 2^A , this lever is shifted to its normal position and the operator at station B completes the movement of lever L^B to its normal position. The apparatus is then restored to its normal condition and the original circuit through relays F^A and F^B and push buttons P^A and P^B is again closed.

Among the advantages of apparatus embodying my invention are the following:

(a) control of the track indicators E^A and E^B by the line circuit. Heretofore indicators of this character have required line wires additional to the line wires used for controlling the lever locks.

(b) The use of the track indicators E^A and E^B for purposes of communication, thus simplifying and reducing the number of indicators, as well as reducing the cost of the installation.

(c) Checking the operation of each lever from the other lever, and indication that the unlock has been received and accepted, this being accomplished without additional indicators.

(d) Means within itself for checking the integrity of the line circuit and the presence

of any derangement, such as a short circuit.

(e) Practical impossibility of securing a false release due to a short circuit.

(f) A line circuit which is self contained, in that it has no line wire in common with any other circuit.

(g) The possibility of furnishing track circuit control for the signal throughout the entire territory between stations, through the use of contacts on the relays F^A and F^B .

Although I have herein shown and described only two forms of apparatus embodying my invention, it is understood that various changes and modifications may be made therein within the scope of the appended claims without departing from the spirit and scope of my invention.

Having thus described my invention what I claim is:

1. In combination, a stretch of railway track extending from a station A to a station B, a traffic lever L^A at station A, a magnet-operated lock for preventing lever L^A from moving to its normal position, a traffic lever L^B at station B, a magnet-operated lock for preventing lever L^B from moving to its reverse position; a relay, a battery and a normally closed push button at each station; an indicator at each station controlled by the associated relay; a circuit including the battery at station B, normal contacts on each of said levers, said two push buttons, and said two relays; track circuits for said stretch for controlling said circuit, means operating when lever L^A is reversed to include the battery at station A in said circuit, means operating when lever L^B is moved to an intermediate position to exclude the battery at station B from said circuit and to include the lock magnet for lever L^B in said circuit, means operating when lever L^A is moved to an intermediate position to include the lock magnet for lever L^A in said circuit, and signals controlled by said levers for governing traffic into said stretch.

2. In combination, a stretch of railway track extending from a station A to a station B, a traffic lever L^A at station A, a magnet-operated lock for preventing lever L^A from moving to its normal position, a traffic lever L^B at station B, a magnet-operated lock for preventing lever L^B from moving to its reverse position; a relay, a battery and a normally closed push button at each station; an indicator at each station controlled by the associated relay; a circuit including the bat-

tery at station B, normal contacts on each of said levers, said two push buttons, and said two relays; track circuits for said stretch for controlling said circuit, means operating when lever L^A is reversed to include the battery at station A in said circuit, means operating when lever L^B is moved to an intermediate position to exclude the battery at station B from said circuit and to include the lock magnet for lever L^B in said circuit, means operating when lever L^A is moved to an intermediate position to include the lock magnet for lever L^A in said circuit, and signals controlled by said levers for governing traffic into said stretch.

3. In combination, a stretch of railway track extending from a station A to a station B, a traffic lever L^A at station A, a magnet-operated lock for preventing lever L^A from moving to its normal position, a traffic lever L^B at station B, a magnet-operated lock for preventing lever L^B from moving to its reverse position; a relay, a battery, a resistance and a normally closed push button at each station, an indicator at each station controlled by the associated relay; a circuit including the battery at station B, normal contacts on each of said levers, said two relays, and the resistance at station A, track circuits for said stretch for controlling said circuit, means operating when lever L^A is reversed to exclude the resistance at station A from said circuit and include the battery at station A in said circuit, means operating when lever L^B is moved to an intermediate position to exclude the battery at station B from said circuit and include the magnet for lever L^B in said circuit, means operating when the movement of lever L^B is continued to the reverse position to exclude the magnet for lever L^B from said circuit and to include the resistance at station B in said circuit, means operating when lever L^A is returned to an intermediate position to include the magnet for lever L^A in said circuit and exclude the battery at station A from said circuit, and signals controlled by said levers for governing traffic into said stretch.

4. In combination, a stretch of railway track extending from a station A to a station B, a traffic lever L^A at station A, a traffic lever L^B at station B, a magnet-operated lock for preventing movement of lever L^A to its normal position, a magnet-operated lock for preventing movement of lever L^B to its reverse position, a lock contact associated with each lever and arranged to be closed when the lever is locked but opened when the lever is unlocked; a relay, a battery, and a normally closed push button at each station; an indicator at each station controlled by the associated relay; a circuit including the battery at station B, normal contacts on said lever, said two push buttons, said two relays, and the lock contact associated

with lever L^B ; track circuits for said stretch for controlling said circuit, means operated when lever L^A is reversed to include the battery and the lock contact at station A in said circuit, means operating when lever L^B is moved to an intermediate position to exclude the battery and the lock contact at station B from said circuit and to include the lock magnet for lever L^B in said circuit, means operating when lever L^A is moved to an intermediate position to include the lock magnet for lever L^A in said circuit, and signals controlled by said levers for governing traffic into said stretch.

5. In combination, a stretch of railway track extending from a station A to a station B, a traffic lever L^A at station A and a traffic lever L^B at station B, a magnet-operated lock for preventing movement of lever L^A to its normal position, a magnet-operated lock for preventing movement of lever L^B to its reverse position; a relay and a battery at each station; an indicator at each station controlled by the associated relay; a circuit including the battery at station B, normal contacts on said levers and said two relays; track circuits for said stretch for controlling said circuit, means operating when lever L^A is reversed to include the battery at station A in said circuit, means operating when lever L^B is moved to an intermediate position to exclude the battery at station B from said circuit and to include the lock magnet for lever L^B in said circuit, means operating when lever L^A is moved to an intermediate position to include the lock magnet for lever L^A in said circuit, and signals controlled by said levers for governing traffic into said stretch.

6. In combination, a stretch of railway track extending from a station A to a station B, a traffic lever L^A at station A, a magnet-operated lock for preventing lever L^A from moving to its normal position, a traffic lever L^B at station B, a magnet-operated lock for preventing lever L^B from moving to its reverse position; a relay and a battery at each station, means for energizing both of said relays from the battery at station B when both of said levers are in nor-

mal positions, means operating when lever L^A is reversed and lever L^B is in an intermediate position to energize both of said relays and the lock magnet for lever L^B from the battery at station A, means operating 55 when lever L^B is in normal position and lever L^A is in an intermediate position to energize both of said relays and the lock magnet for lever L^A from the battery at station B, an indicator at each station controlled by 60 the associated relay, and signals controlled by said levers for governing traffic into said stretch.

7. In combination, a stretch of railway track extending from a station A to a station B, a traffic lever L^A at station A and a traffic lever L^B at station B, a magnet-operated lock for preventing movement of lever L^A from its normal indication position to its normal position, a magnet-operated lock 65 for preventing movement of lever L^B from its reverse indication position to its reverse position; a relay, a battery and a normally closed push button at each station; an indicator at each station controlled by the 70 associated relay; a circuit including the battery at station B, normal contacts on said levers, said two push buttons, and said two relays; track circuits for said stretch for controlling said circuit, means operating 75 when lever L^A is moved to a position between reverse indication and reverse positions to exclude the relay at station A from and include the battery at station A in said circuit, means operating when lever L^B is 80 moved to its middle position to exclude the battery and the relay at station B from and include the lock magnet for lever L^B in said circuit, means operating when lever L^A is moved to its reverse position to restore the 85 relay at station A to said circuit, means operating when lever L^B is moved to its reverse position to exclude the lock magnet for lever L^B from and restore the relay at station B in said circuit, and signals controlled by 90 95 said levers for governing traffic into said stretch.

In testimony whereof I affix my signature.

HENRY W. GRIFFIN.
